DESCRIPTION

U.S. PATENT DOCUMENTS

FIG. 1 is a front view of the claimed design.

2,050,210 A * 8/1936 Griffin D2/961
3,086,520 A * 4/1963 Scholl D2/961
D300,084 S * 3/1989 Ita et al. D2/961
D324,761 S * 3/1992 Soo-Kwan D2/961
5,098,421 A 3/1992 Zook
D353,259 S * 12/1994 Schroer, Jr. D2/961
D354,616 S * 1/1995 Schroer, Jr. D2/961
D376,900 S * 12/1996 Seydel et al. D2/968
D420,210 S * 2/2000 Allen D2/961
D420,787 S * 2/2000 Robinson et al. D2/961
6,038,793 A 3/2000 Kendall

FIG. 2 is a rear view of the claimed design.

FIG. 3 is a left side view of the claimed design.

FIG. 4 is a right view of the claimed design.

FIG. 5 is a top view of the claimed design.

FIG. 6 is a bottom view of the claimed design; and,

FIG. 7 is an isometric view of the claimed design in use.

The hidden lines of FIG. 7 are environmental matter and do not constitute a part of the claimed design.
